ANDRÉ GUÉRET, OF PARIS, FRANCE.

MULTICYLINDER INTERNAL-COMBUSTION ENGINE.

1,164,504.

Specification of Letters Patent. Patented Dec. 14, 1915.

Application filed August 10, 1911. Serial No. 643,440.

To all whom it may concern:

Be it known that I, ANDRÉ GUÉRET, engineer, a citizen of the Republic of France, residing at 1 Rue Picot, Paris, France, have 5 invented certain new and useful Improvements in Multicylinder Internal-Combustion Engines, of which the following is a specification.

This invention relates to four stroke cycle 10 internal combustion engines with several cylinders, and distribution by such means as slide valves proper or flat valves, and, more particularly, sleeve valves or liners.

One object of the invention is to enable 15 the use in such engines, without necessitating a concurrent increase of the amount of clearances, the arrangement already specified, while maintaining the usual arrangement of the connecting rods and of the respective pistons of the various cylinders of 20 the said engines, and providing for each of the said cylinders only one slide valve without bringing about any premature uncovering of the ports, the slide valves used 25 being arranged in a pair or pairs in such a manner that both the admission and exhaust of gases are controlled by the corresponding slide valves.

The invention consists substantially in 30 using in the engines of the class specified such mutual arrangement of the slide valves that the time each cylinder is controlled by the noncorresponding slide valves is regulated by the corresponding slide valve; or, 35 in a similar mutual arrangement of the said slide valves, and particular association of the same relatively to the corresponding respective pistons, that the latter will contribute to the fulfilment of the function of 40 the said slide valves.

The invention further consists in the constructions and arrangements which will be understood from the following description and the accompanying drawings which illustrate preferred structures embodying the invention.

Figure 1 is a vertical axial section on the line 1—1 of Fig. 2 of a vertical two-cylinder engine embodying the features of the inven-

tion. Fig. 2 is a vertical section on the line 50 2—2 of Fig. 1 or in a plane at right angles to that shown by the latter figure. Figs. 3, 4 and 5 show respectively in horizontal cross-section on the line 3—3 of Fig. 1, in similar section on the line 4—4 of Fig. 1, and in 55 similar section on the line 5—5 of Fig. 1, the same engine. Fig. 6 is a vertical section on the line 6—6, Figs. 3, 4 and 5. Figs. 7 and 8 are detail perspective views of the sleeve valves.

According to the features of the invention to which the drawings more particularly refer, and when it is desired to construct a vertical internal combustion two cylinder engine with four-stroke cycle and 65 sleeve valves, the construction is as follows:

a' and a^2 designate a pair of twin cylinders which are made of such a bore that it is possible to insert between them and the pistons b' and b^2 sleeve valves c' and c^2 , 70 and the whole is provided in the web a , which is common to the two cylinders, with a pair of ports d' and d^2 passing through the said web and situated in one and the same horizontal plane. One of these ports is 75 located at the front of the web a and the other at the back of said part.

In the cylinders a' and a^2 two ports e' and e^2 are provided, one for each of the cylinders, situated, like the ports d' and d^2 80 in the same horizontal plane and extended toward the front by respective conduits f' and f^2 , by means of which the said ports e' and e^2 are connected to a branch g arranged in such a manner that it can be utilized 85 as a common or joint inlet branch.

In those parts of the device which adjoin the said web a , are provided two ports h' and h^2 , one for each of the cylinders, and situated in different horizontal planes, the 90 port h' being located adjacent to the rear portion and near the bottom of the cylinder a' and extended toward the rear by a conduit i' connected to a branch j^2 arranged in such manner that it can be utilized as an 95 exhaust branch for the cylinder a^2 . The second port h^2 is located at the front and near the top of the cylinder a^2 extended to-

ward the front by a conduit i' connected to a branch j' arranged in such a manner that it can be utilized as an exhaust branch for the cylinder a' .

5 The sleeve valves c' and c^2 are constructed as follows: The sleeve valve c' has a port k' adapted to be shifted into coincidence with the port e' of the cylinder a' , and also said sleeve is provided with a port l' that can be 10 in a similar manner moved to coincide with the port d' , and said sleeve is also provided with a recess l^2 in the lower portion of the outer surface which produces with the said web a of the cylinders a conduit m^2 of such 15 construction that when the upper edge of the said recess is at a higher level than that of the ports d' and d^2 , it establishes communication between the second of the said ports and the conduit i^2 , and consequently the 20 branch j^2 .

The sleeve valve c^2 has a port k^2 of such construction that it can be brought to coincide with the port e^2 of the cylinder a^2 , and a port l^3 such that it can be similarly brought 25 to coincide with the port d^2 and provided with a recess in the upper part of its outer surface which produces with the said web a of the cylinders a conduit m' , and when the bottom edge of the said recess is at a lower 30 level than that of the ports d' and d^2 it establishes communication of the port d' with the conduit i' and consequently with the branch j' .

35 The sleeve valves c' and c^2 are introduced from the top after the removal of the respective covers of the cylinders a' and a^2 into the said cylinders. On the base of each of the said sleeve valves is mounted a sleeve n' or n^2 , and the said covers are replaced.

40 Into the lower portions of the sleeves thus put in place are introduced from below the pistons b' and b^2 above referred to. The said pistons b' and b^2 are connected by means of rods o' and o^2 to the cranks p' and 45 p^2 of the crank shaft p arranged at an angle of 180° relatively to each other. The valve sleeves or liners c' and c^2 are connected in the same way, by means of the said sleeves n' and n^2 and connecting rods q' and q^2 to 50 the cranks r' and r^2 of an additional crank shaft r having the said cranks thereof arranged at an angle of 90° relatively to each other; the crank shaft r being connected in its turn, by means of chain wheels r^3 and a 55 chain r^4 , to the shaft p in such a manner that when the latter rotates, the said additional or supplementary crank shaft is driven at half the speed. Owing to the above, and if the respective keying of the 60 cranks has been suitably effected, particularly in the manner indicated in the drawing, the operation will take place in the following manner as regards the cylinder a'

and of course, as is obvious, in a substantially similar manner as regards the cylinder a^2 .

Assuming in the first place that the various movable parts are in the positions in which they are shown in Fig. 6 corresponding to the end of exhaust in the cylinder a' 65 in question, there will take place successively: First, there is an ascent of the liner c' , and when it arrives at the top of the stroke there is coincidence between its port k' and port e' , and communication between its port l' and the port d' is cut off; and when a descent of the piston b' takes place, a suction is set up through the conduit i' into the branch j' . Then, and upon further descent of the liner c' , the coincidence between its port k' and the port e' is broken, and communication between its port l' and the port d' is not reestablished; and also, such a continuation of the descent of the piston b' that it arrives approximately at the 70 moment of breaking of the said coincidence at the bottom of the stroke which corresponds to the end of the suction. Then, there occurs such a continuation of the descent of the liner c' that communication between its port l' and the port d' is reestablished, and at the same time such movement of the liner c^2 that the lower edge of its recess assisting in forming the conduit m' , which edge had been already made previously to pass the upper edge of the port d' , should remain above the said upper edge of the port d' , and also such a renewed rising of the piston b' that it produces compression of the charge drawn in during the preceding stroke, which compression is rendered possible by the obturation effected by the liner c^2 .

75 Then, such a continuation of the various movements just referred to occurs that the piston b' first arrives at the position of ignition, and then at the top of the stroke, the ports k' and l' remaining at the same time disconnected, the former without any assistance from the port e' and the latter being disconnected from the conduit m' by the liner c^2 .

80 Then, the liner c' arrives at the bottom of the stroke and rises again, without this leading in practice to any particular result, either as regards the port k' or the port l' , which both remain in the same state as that referred to in the preceding paragraph, and for the same reasons; and also the piston b' descends again and is thus 85 made to accomplish its working stroke. Then, the rising of the liner c' continues so that communication is reestablished between its port l' and the port d' , and simultaneously such a shifting of the liner c^2 occurs 90 that the bottom edge of its recess contribut-

ing to the formation of the conduit m' moves below the upper edge of the said port d' , thus establishing communication between the interior of the cylinder a' and the 5 said conduit m' , and consequently the exhaust branch j' ; also a continuation of the renewed descent of the piston b' is effected and a lead produced in the exhaust, the piston b thus being made to complete its working 10 stroke. Then, such a continuation of the various movements just referred to is produced that after having returned to the bottom of the stroke, the piston b' rises again, producing exhaust, the port k' remaining at 15 the same time disconnected without any assistance from the port e' , and the port l' in communication, by means of the liner c^2 , with the conduit m' . Finally, such a continuation of the renewed rising of the liner 20 c' is effected that it passes at one side with the lower edge of its port l' the upper edge of the port d' , and consequently shuts off communication of the interior of the cylinder a' with the conduit m' and at the other 25 side coincides, as regards the upper edge of its port k' , with the lower edge of the port e' ; and also such a continuation of the renewed rising of the piston b' is effected that it again arrives at the top of the stroke, the 30 whole corresponding to the return of the various movable parts to their initial position.

The particular method of construction above described makes it possible to insure a very great perfection of working. Still 35 better results can, however, be obtained by adopting, as has been assumed to have been made in the example illustrated in the drawings, in addition to the arrangements already described, such an arrangement, 40 with regard to the choice of position of the ports to be made in the cylinders relatively to that which the respective pistons of the same cylinders occupy at the top of the stroke in the same, that the said pistons, as 45 shown by Fig. 6, themselves act as obturating devices, more particularly from the moment of the ignition to a certain point of the working stroke. In that way the said ports, or more particularly those of the 50 sleeve valves, are protected from contact with hot gases during the time when the gases in question have the highest temperatures, so that the ports in question are better protected, and, moreover, a kind of concentration of the force produced by the 55 explosion on the piston is obtained.

It is obvious that the invention is by no 60 means limited to those details of construction which have been more particularly described, but comprises, on the contrary, all modifications, namely those where, in view of its application to six-cylinder engines, the six cylinders to be used are formed into

two groups of three cylinders each, the three systems of distribution of the said cylinders 65 being combined simultaneously in twos.

What is claimed is:

1. In a four-cycle multi-cylinder internal combustion engine, the combination of a pair of cylinders and pistons, the cylinders 70 each having an inlet port communicating with a common inlet branch, the cylinders also having exhaust ports, a web between the cylinders having a pair of ports adapted to have individual communication with 75 the like ports of the cylinders adjacent thereto, and sleeve valves movably mounted in the cylinders also provided with ports and individually and simultaneously operable in such manner that each sleeve valve 80 controls the inlet and exhaust of its cylinder and also one of the ports of the companion cylinder.

2. In a four-cycle multi-cylinder internal combustion engine, the combination of a 85 pair of cylinders, a slide valve reciprocably mounted in each cylinder, a piston in each slide valve, the cylinders each having a port communicating with a common inlet branch, the cylinders also having exhaust 90 ports, a web between the cylinders having a pair of ports to communicate with exhaust ports of the cylinders adjacent thereto, and means for operating the slide valve and piston of each cylinder in connected relation 95 in such manner that the piston covers the inlet and exhaust ports of the said slide valve at the end of the compression stroke and at the beginning of the working stroke.

3. In a four-cycle multi-cylinder internal 100 combustion engine, a pair of cylinders, each cylinder having an inlet port provided in the wall thereof, a common inlet branch communicating with said cylinder inlet ports, the cylinders also having exhaust 105 ports, a web between the said cylinders provided with two horizontal ports, a slide valve reciprocating in each cylinder and each having an inlet port corresponding to the inlet port of its cylinder, the said slide 110 valves also being each provided with an exhaust port individually corresponding to one of the horizontal ports of the web and also provided with a recess to correspond to the remaining horizontal port of the web, 115 a reciprocating piston in each slide valve, the web also having two exhaust conduits respectively above and below the said horizontal ports thereof to individually coöperate with the respective recesses of the slide 120 valves, and means for controlling the reciprocating motion of the slide valves whereby each of said valves control the inlet and exhaust ports of its respective cylinder and simultaneously controls the exhaust of an- 125 other cylinder.

4. In an engine of the character specified, the combination of a pair of cylinders provided with exhaust and inlet ports, a slide valve reciprocatingly mounted in each cylinder and having ports to control the ports of its respective cylinder, a piston in each slide valve, and means for operating the slide valve and piston of each cylinder in connected relation in such manner that the 10 piston covers the inlet and exhaust ports of

its respective slide valve at the end of the compression stroke of said piston and at the beginning of the working stroke.

In testimony whereof I have hereunto set my hand in presence of two subscribing witnesses. 15
